CAR-SEAT BASE

Oiva E. Hill, Gardner, Mass., assignor to Heywood-Wakefield Company, Gardner, Mass., a corporation of Massachusetts

Application July 21, 1939, Serial No. 285,711

5 Claims. (Cl. 155—96)

This application relates to improvements in car-seat bases of the type which are reversed from one position to the other by rotation accompanied by a shifting movement away from the wall of the vehicle during the initial portion of the rotative movement, and back toward the wall during the final portion of the rotative movement. The invention relates more particularly to a seat base of this kind having its reversing movements controlled by cams cooperating with a pair of cam followers mounted on the movable seat carriage and arranged in the front-to-rear median plane of the carriage so as to exchange places with respect to the stationary pedestal when the seat is reversed from one position to the other, as, for example, the seat bases described and illustrated in my copending applications Serial No. 200,825, filed April 8, 1938, which matured into Patent No. 2,215,817 on September 24, 1940, and Serial No. 237,233, filed October 27, 1938.

It is an object of the present invention to provide a rotating car-seat base of the foregoing type which is simple and inexpensive in structure, which is rugged, and which operates smoothly during the entire movement of the seat from one position to the other. Cam-controlled reversing mechanisms of the kind described in said applications are characterized by the use of one of the pair of cam followers as a pivot for the initial and final portions of the reversing movement so as to swing the seat away from the wall to clear the wall in turning, and then to swing the seat back close to the wall at the end of the reversing movement. Between these portions of the reversing movement, the pivot shifts and the seat rotates about one or more other pivots. According to the present invention, auxiliary cams and followers are provided, these being so constructed and arranged that the shifts in pivot axes, instead of being abrupt, are progressive or continuous away from the initial axis, then back to the final axis. According to this invention, also, the path described by the center point of the seat carriage is free from abrupt changes in direction. Furthermore, side-lash at critical parts of the reversing movement is reduced, and the stresses on the various portions of the cam edges are more evenly distributed, so that the mechanism has a greatly increased life.

Various other advantageous features are to be found in the embodiments of the invention described herein and illustrated in the drawings, of which

Figure 1 is an end elevation of a car seat having a base embodying the invention.

Figure 2 is a plan view of the same showing portions of adjacent seats and the vehicle wall.

Figure 3 is a section on the line 3—3 of Figure 2.

Figure 4 is a section on the line 4—4 of Figure 3.

Figure 5 is a perspective view of a socket member employed in the seat base.

Figure 6 is a section on the line 6—6 of Figure 3.

Figure 7 is a section on the line 7—7 of Figure 6.

Figure 8 is a diagrammatic plan view of a cam system equivalent to that shown in Figure 6.

Figures 9, 10, 11 and 12 are diagrammatic plan views of modified forms of cam systems.

The invention may be embodied in various forms of seats or chairs but is shown as embodied in a car seat such as is often employed in railway cars where it is desirable to reverse the position of the seats in accordance with the direction in which the car is to be operated.

Figure 1 shows a chair including a seat cushion 20, arm rests 22, a back 24, and a base generally indicated at 26. The base may be of the central pedestal type or may be supported at its ends. The former is indicated on the drawing.

As shown in Figure 2, it is desirable to mount the seats as close to the adjacent vehicle wall 30 as possible so that maximum aisle width can be had. Since it is necessary that the corners of the seat clear the wall when the seat is being rotated to reverse its position, the seat base is constructed with mechanism by which the seat moves away from the wall during the initial portion of its reversing movement and back toward the wall during the final portion of such movement. To this end, the base 26 is constructed with a stationary pedestal 32 having a horizontal top 34 in which is an opening 36 defining internal edges of the pedestal top which serve as cam surfaces. Cooperating with these cam surfaces are a pair of cam followers 40 and 42 which, as shown, may be in the form of suitable rollers rotatably mounted on vertical studs 44 and 46 which are secured to a transverse bar 48 and project upwardly therefrom. The studs 44 and 46 project through a portion of the seat carriage 50 on which the seat 20 with its arms rests 22 and back 24 is directly mounted. The upper portions of the studs 44 and 46 are preferably threaded as indicated in Figure 3 to receive nuts 52 and 54 to secure the carriage to the bar 48.

Figure 4 is a section on the line 4—4 of Figure 3 showing the cam surfaces 36 and 38, the cam followers 40 and 42, and the transverse bar 48. The nuts 52 and 54 are shown in Figure 3. The cam surfaces 36 and 38 are shown in Figure 5. Figure 6 is a section on the line 6—6 of Figure 3 showing the cam surfaces 36 and 38, the cam followers 40 and 42, and the transverse bar 48. The nuts 52 and 54 are shown in Figure 3. The cam surfaces 36 and 38 are shown in Figure 5. Figure 7 is a section on the line 7—7 of Figure 6 showing the cam surfaces 36 and 38, the cam followers 40 and 42, and the transverse bar 48. The nuts 52 and 54 are shown in Figure 3. The cam surfaces 36 and 38 are shown in Figure 5. Figure 8 is a diagrammatic plan view of a cam system equivalent to that shown in Figure 6. Figures 9, 10, 11 and 12 are diagrammatic plan views of modified forms of cam systems.

As indicated in Figures 4 and 6, the bar 48 may be constructed in a single piece in the shape of an open channel having transverse webs 56 and 58. At one end of the bar 48 is a fan-shaped end portion 60 with an arcuate edge. At the other end of the bar 48 is a similarly fan-shaped end piece 62 which, instead of being integral with the bar 48, is on the end of a plunger 64 which is thrust into the bar 48 and is movable lengthwise thereof. A reduced portion 66 of the plunger 64 projects through a hole in the web 58, a pin 68 being thrust through the reduced portion 66 to limit the outward movement of the end piece 62. A compression spring 70 bears against the web 58 at one end and against a shoulder 72 on the plunger 64 at the other end so as to press the end piece 62 as far outward as the pin 68 will permit. As is evident from Figure 4, the end piece 62 can be pressed inwardly against the spring 70. The end pieces 60 and 62 are adapted to fit in curved recesses 74 in socket members 76 which are preferably forgings welded or otherwise secured to the pedestal 32. The curved edges of the end pieces 60 and 62 are preferably concentric respectively with the axes of the studs 44 and 46 for the reasons hereinafter explained. Below the fan-shaped portion of the end piece 60 is a vertical web 78 which is adapted to engage a stop element 80 formed on the socket member 76. Immediately above the fan-shaped elements 60 and 62 are hold-down elements 81 which project under the portions of the top 34 adjacent to the aperture 36 to maintain the seat carriage upright on the top of the pedestal.

As indicated in Figure 5, the stop member 80 may be in the form of a suitable lug within the curved recess 74, the lug 80 being preferably midway between the upper and lower edges of the socket member 76 so that the member can be used on either the front or rear wall of the pedestal, thus eliminating the necessity of making rights and lefts.

As shown in Figure 6, the opening 36 is roughly triangular in shape, the corners of the triangle being sockets adapted to receive the cam followers 40 and 42. A side 82 of the triangle is substantially straight and is parallel to the ends of the pedestal, the sockets at the ends of this side being likewise in a line parallel to the ends of the pedestal. The cam followers 40 and 42 are normally seated in the sockets at the ends of the straight edge 82 and are disposed in the median longitudinal or front-to-rear plane of the seat carriage. During the initial portion of a reversing movement, the cam follower 40 is kept in its socket or corner of the opening 36 by engagement of the web 78 with the stop lug 80 and by engagement of the follower 42 with an arcuate edge portion 84 of the opening 36 which is concentric with the opposite socket, and serves as a temporary pivot for the initial rotative movement of the seat. During such initial movement, the cam follower 42 moves along the arcuate edge portion 84 of the cam until it reaches a point 86. At this point the curve of the cam edge is reversed so that the follower 42 no longer retains the follower 40 in its corner. When the follower 42 reaches the point 86, however, an auxiliary cam follower 90, which, as shown, is located on the bar 48 midway between the followers 40 and 42 and which projects downwardly from the bar, effectively engages the edge 92 of a cam member 94 which is mounted below the top plate 34. The cam edge 92 is concave at

the point where it is engaged by the follower 90, the radius of curvature of this portion of the cam edge being considerably greater than that of the follower itself. Thus, when the follower 90 engages the edge 92, its progress is not abruptly stopped nor is its direction abruptly changed. The curved edge 92 guides the follower 90 in a more gradual change of direction. As the follower 90 starts its movement along the edge 92, the follower 40 moves away from its corner and along the cam edge 82. As seen in Figure 6, the initial movement of the follower 40 toward the right takes place while the follower 90 is still moving downward and toward the left. Since the followers 40 and 90 are thus moving in opposite directions at the same time, it is evident that at that moment the axis of rotation of the seat carriage is between the two followers. Thus, by reason of the shape of the edge 92, the axis of rotation of the seat is progressively or continuously shifted from the follower 40 along the bar 48 to the follower 90. As the follower 90 travels along the edge 92 it soon changes its direction so as to move toward the right. Meanwhile, the follower 42 is moving slowly toward the left so that at this time the axis of rotation of the seat carriage is moving between the follower 90 and the follower 42. The cam edge 84 ends in a corner or socket 94 which is shaped to receive the follower 42 when the carriage reaches the mid-point of its turn. At that instant, the follower 42 is the pivot point or fulcrum about which the seat carriage swings. Immediately thereafter the follower 42 begins to move out of the socket 94 and to move toward the left. Since at this time the follower 90 is moving toward the right along a portion 96 of the auxiliary cam edge, it is evident that the pivot or axis of rotation of the seat carriage is shifting along the bar 48 from the follower 42 to the follower 90. When the follower 90 reaches a point 98, it is for an instant the pivot of the seat carriage. During further movement of the carriage, the axis of rotation shifts along the bar 48 until it reaches the follower 40 when this follower reaches the right-hand corner of the opening 36 previously occupied by the follower 42, where further progress is positively stopped by engagement of the web 78 with the stop lug 80 on the right-hand socket member 76. At this point, the follower 42 has reached a point 100 on the cam edge at which point the cam edge extends in an arcuate curve to the left-hand corner of the opening 36, this curve being concentric with the socket now occupied by the follower 40. When the follower 42 passes the point 100, it thereupon becomes effective to retain the follower 40 in the right-hand corner while the follower 42 travels along the edge to the left-hand corner originally occupied by the follower 40. The movement of the seat carriage is thus characterized by the absence of any abrupt shift in the axis of rotation, and consequently by the absence of any abrupt change in the direction of movement of the center point of the seat carriage, as indicated in Figure 8.

The path followed by the cam follower 90 (and hence by the carriage center) during a reversing movement of the seat is illustrated by a broken line in Figure 8 which shows diagrammatically a pedestal top having an opening 36 identical with that shown in Figure 6 and an auxiliary cam member having cam edges identical with those of the cam member 94, these edges being extended to the limits of movement of the cam follower

90. A seat-base mechanism made as shown in Figure 8 would operate in identically the same manner as that shown in Figure 6, but, since the follower 90 does not become effective until it reaches the point 92, the upper portion of the auxiliary cam plate may be omitted, as shown in Figure 6, to save weight.

Figure 9 shows a modified form of the invention including a pedestal top 110 having an opening 112 therein defined by a series of cam edges along which a pair of followers 114 and 116 move during a reversing movement of the seat carriage. These cam followers may be mounted on a bar 118 which also carries a pair of auxiliary cam elements 120, 122. The auxiliary cam followers are preferably in a different plane from the cam followers 114 and 116 so as to engage the cam edges of an auxiliary cam member 124. During the rotation of the seat carriage, the cam follower 114 serves as the initial pivot or axis of rotation for the carriage and the cam follower 116 moves along an arcuate edge 126 which is concentric with the axis of the cam follower 114. As the bar 118 swings about the follower 114 as a pivot, together with the seat carriage of which it is a part, the auxiliary cam follower 120 reaches the cam edge of the plate 124 at the point 128. At this point, the cam follower 120 becomes effective, resulting in a progressive shift of the axis of rotation of the carriage along the bar 118 from the follower 114 to the follower 120. Soon afterwards, the auxiliary cam follower 122 engages the cam edge of the plate 124 at the point 130, whereupon the follower 122 becomes effective, resulting in a progressive shift of the axis of rotation along the bar 118 to the follower 122. The follower 122 thus becomes the momentary pivot when the seat carriage reaches the mid-point of its reversing movement. The axis of rotation then moves progressively in the opposite direction to the follower 120 and eventually back to the follower 114 when the latter reaches the right-hand corner of the aperture 112. The broken line with arrows shows the path followed by the center of the seat carriage during a reversing movement.

Figure 10 shows a pedestal top 132 with an opening 134 therein defining cam edges along which a pair of cam followers 136 and 138 move during reversing movement of the seat carriage. The cam followers 136 and 138 are at opposite ends of a spacer bar 140 which is virtually a part of the seat carriage which rests on the top 132. Below the top 132 is an auxiliary cam plate 142 having cam edges engageable by an auxiliary cam follower. This cam follower actually comprises two followers 144 and 146. During the initial portion of a reversing movement of the seat carriage, the follower 136 remains in its corner while the follower 138 moves along an arcuate edge portion of the opening 134 concentric with the axis of the follower 136. When the follower 138 reaches the end of this arcuate portion, the auxiliary follower 144 engages the cam edge of the plate 142 and becomes effective to shift the axis of rotation of the carriage progressively from the follower 136 to the follower 138. Soon afterwards the follower 146 becomes effective to shift the axis of rotation of the seat carriage to its own center, the follower 136 being the momentary pivot as the seat carriage is passing the mid-point of its reversing movement. The further action of the cam followers is to shift the axis of rotation of the seat carriage progressively back along the bar 140 until the fol-

lower 136 again becomes the pivot when it reaches the right-hand corner of the aperture 134. The final portion of the rotating movement of the seat carriage takes place as the follower 138 moves along an arcuate edge portion of the aperture 134 until it reaches the left-hand corner originally occupied by the follower 136. The path of the carriage center is shown by the broken line.

10 Figure 11 shows another form of seat-reversing cam structure including a pedestal top 150 having an aperture 152 therein defining cam edges along which a pair of followers 154 and 156 are adapted to move during the reverse movement of the seat carriage. These cam followers are at the ends of a bar 158 which also carries an auxiliary cam follower 160. The latter is approximately in a semi-circular form and is adapted to rotate in a circular recess 162 in a cam plate 164 mounted below the top 150. During the reversing movement of the seat carriage, the follower 154 serves as a pivot while the follower 156 moves along an arcuate cam edge until the auxiliary cam follower 160 enters the circular notch 162. Thereupon the follower 160 becomes effective and serves as the pivot for the seat carriage until the follower 156 reaches the right-hand corner of the aperture 152, whereupon the follower 154 again serves as the pivot while the follower 156 moves up into the left-hand corner.

Figure 12 shows another form of cam mechanism including a pedestal top 170 having an aperture 172 therein defining cam edges along which move a pair of triangular shoes 174 and 176. These shoes are each pivoted on the ends of a bar 178 to which the seat carriage may be secured. Below the top 170 is an auxiliary plate 180 having cam edges engaged by an auxiliary cam follower 182 which is mounted on the bar 178. The aperture 172 is shaped with notches 184, 186, 188 and 190. As shown in Figure 12, the shoe 174 has one of its corners engaging in the notch 184 when the seat carriage is in one of its positions of use. During the initial portion of the reversing movement, the shoe 174 remains stationary while the shoe 176 slides along an arcuate cam edge. At the same time the auxiliary cam follower 182 moves along the cam edge of the plate 180 until it reaches the point 192, whereupon the auxiliary cam follower 182 becomes the temporary pivot while the shoe 174 moves along the upper edge of the opening 172 until it enters the notch 190. The shoe 174 thereupon becomes a pivot for the final portion of the reversing movement of the seat carriage, during which movement the shoe 176 moves along another arcuate edge portion of the aperture 172 until one of its corners enters the notch 186.

It is evident that various modifications and changes may be made in the embodiments of the invention herein shown and described without departing from the spirit or scope thereof as defined in the following claims.

65 I claim:

1. A reversing car-seat base comprising a stationary pedestal having a pair of spaced sockets arranged in a line parallel to the ends of the pedestal, a seat carriage movable on said pedestal, a pair of cam followers on said carriage normally disposed in said sockets, an arcuate cam surface on said pedestal concentric with one of said sockets and engageable by one of said cam followers during the initial portion of a reversing

movement of the seat carriage to hold the other cam follower in its socket, cam means on said pedestal and carriage for causing said other follower to shift from its socket to the other socket during the intermediate portion of said reversing movement, and a second arcuate cam surface on said pedestal concentric with said other socket and engageable by said one follower during the final portion of said reversing movement to hold said other follower in said other socket.

2. A reversing car-seat base comprising a pedestal having a horizontal top with cam edges, a seat carriage movable on said top, a pair of cam followers carried by said carriage in the front-to-rear median plane thereof and arranged to engage said cam edges, an auxiliary cam follower mounted on said carriage between said pair of followers, and an auxiliary cam on said pedestal engageable by said auxiliary follower, said cams being arranged and shaped so that one of said pair of followers serves as a center of rotation for the initial and final portions of the reversing movement of the carriage, and the axis of rotation shifts progressively from said one follower toward the other and back during the intermediate portion of the reversing movement of the carriage.

3. A reversing car-seat base comprising a stationary pedestal, a seat carriage movable thereon and means for guiding reversing movement of said carriage on said pedestal, said guiding means including a series of three cam followers mounted on said carriage in the longitudinal median thereof, a pair of sockets on said pedestal normally engaged by the end followers of said series, a pair of arcuate cam surfaces concentric respectively with said sockets and engageable by one of said end followers to maintain the other end follower in said sockets to act as a pivot during the initial and final portion of a reversing movement, and an auxiliary cam surface en-

gageable by the intermediate follower of said series and shaped to shift the pivot axis of the seat by stages away from and back to said other end follower during the intermediate portion of the reversing movement.

4. A reversing car-seat base comprising a stationary pedestal with a horizontal top, a seat carriage supported on said top and rotatable between two oppositely facing positions for use, a pair of cam followers on said carriage arranged in the front-to-rear median plane thereof when the carriage is in either of its positions for use, an auxiliary cam follower mounted on said carriage between said pair, and cam means on said pedestal engageable by said followers to guide the reversing movements of said carriage so that one of said pair of followers acts as a turning pivot for the initial and final portion of reversing movements of said carriage and the center of the carriage follows a path in which there is no abrupt change of direction.

5. A reversing car-seat base comprising a stationary pedestal with a horizontal top, a seat carriage supported on said top and rotatable between two oppositely facing positions for use, a pair of cam followers on said carriage arranged in the front-to-rear median plane thereof when the carriage is in either of its positions for use, an auxiliary cam follower mounted on said carriage in the central vertical axis thereof, and cam means on said pedestal engageable by said followers to guide the reversing movements of said carriage, said means being constructed and arranged so that the center of rotation of the carriage is initially in one of said pair of cam followers and shifts successively, during a reversing movement of said auxiliary follower, the other of said pair back to said auxiliary follower and then to said one follower for the final portion of the reversing movement.

OIVA E. HILL.
